UNITED STATES PATENT OFFICE.

ROY AUSTIN, OF LONDON, ENGLAND.

ILLUMINATED SIGN.

Application filed March 19, 1927, Serial No. 176,606, and in Great Britain March 13, 1926.

The present invention relates to illuminated signs and like displaying devices of the type in which the words or designs to be displayed or advertised are formed in or marked on a front screen or plate adapted to be illuminated from the rear.

It has been proved by experiment that, in the case of a sign exteriorly illuminated by daylight, the luminosity of the displayed matter can be considerably enhanced with remarkable effect by employing a diffusing screen or plate of a proper degree of opacity onto which the light entering the sign is reflected directly or without being first caused to pass through or fall upon any coloured or other light-absorbing surface.

It has been found that the requisite degree of diffusion as aforesaid can best be obtained by employing a glass screen or plate of roughened surface, and this invention consists in an exteriorly illuminated sign or device of the character defined consisting of a V shaped box or casing which is open as to the upper portion thereof and comprising essentially a screen or plate of ground or frosted glass which is disposed immediately behind the front screen or plate whereby the advertisements or notices are displayed and a sheet or panel of corrugated or ribbed mirrored glass which extends at an inclination at the rear of the whole of the matter to be displayed, whereby the full unobstructed light entering the sign from above is reflected directly upon the rear surface of the said screen or plate of ground or frosted glass and is diffused therethrough over the entire advertisements or notices with the effect that the latter are strongly and uniformly illuminated from the rear and appear as solid luminous letters or designs when viewed from the front from any angle or position. The said invention also consists in certain details in the construction and arrangement of the said sign as hereinafter described and set forth in the claims.

An illuminated sign or device in accordance with the said invention is illustrated by way of example in the accompanying drawing, in which Figures 1 and 2 are, respectively, a perspective view and a cross-sectional view of the said sign or device, the section being taken along the line 2-2 in Figure 1.

The sign or device illustrated consists of a box or casing of the usual V shape which is formed by side triangular walls α and by

a front rectangular frame α^1 and a rear rectangular wall α^2 , and which is open as to the upper portion thereof. The front portion or face of the box or casing comprises an opaque screen or plate b composed of suitable material wherein the words or other matters to be displayed are cut-out or stencilled as indicated at b^1 , the front screen or plate b conveniently consisting of a comparatively thin sheet of metal which can be readily cut-out or stencilled as required and which is preferably provided with an outer covering screen c composed of glass or other suitable transparent material. The rear rectangular wall α^2 of the box or casing extends outwardly at an angle in the neighbourhood or 45 degrees substantially to the level of the upper portion of the front rectangular frame α^1 , and serves as a backing or support for the reflecting sheet or panel f of corrugated or ribbed mirrored glass.

The screen or plate of ground or frosted glass d is disposed in close proximity to the rear of the front screen or plate b so as to form a diffusing background for the whole of the letters or designs to be displayed. If desired, the background thus formed may be coloured or tinted by means of a screen or sheet e composed of a suitable transparent or translucent material, such as gelatine, of the requisite colour or tint, which is interposed between the diffusing screen or plate d and the front screen or plate b .

In the example illustrated, the sign or device is provided with inner triangular side plates g which are inwardly bent as to the front and rear portions thereof, as indicated at g^1 , and which are dimensioned in width, as best seen in Figure 2, so that the hereinbefore described screens and reflector are thereby maintained in their respective positions as aforesaid against the front frame α^1 and the rear wall α^2 , the retaining plates g being each attached to its adjacent side wall α by means of a screw-bolt h and nut h^1 . The side walls α are also furnished with inwardly bent upper portions α^3 which are cut-away at the front and rear extremities thereof, as shown at k^1 and k^2 , so as to permit of the insertion or removal of the above-said screens and reflector when the retaining plates g are detached and removed from the sign. Thus, the device can be easily assembled or dismantled, and any of the screens or the reflector thereof can be expeditiously changed or replaced as required.

In cases where the sign is to be suspended for displaying purposes, the upper bent portions a^3 of the side walls a are each conveniently formed with a series of perforations k which are adapted to afford on each side of the device a means of attachment for a hanging cord or chain, so that the sign or device can be readily suspended and adjusted in the position or at the inclination affording the most advantageous view.

When artificial light is utilized for illuminating the displayed words or other matters, the source of light may be located above the sign in a position calculated to produce the best lighting effect, or the sign itself may be adjusted at the most effective inclination relative to the said source of light in the hereinbefore described manner. The sides of the device, if desired, may be furnished with suitably disposed inner reflecting surfaces, and the upper portion of the sign, instead of being left open as aforesaid, may be covered with a screen or plate composed of glass or other suitable transparent material.

25 What I claim is:—

1. An exteriorly illuminated sign comprising in combination, a V shaped casing open as to the upper portion thereof and consisting of a front frame and rear wall and of two side walls, a screen adapted to display the matter to be exhibited and located within the said front frame, a plate of ground glass disposed immediately behind the said front displaying screen, a reflecting panel of ribbed mirrored glass supported by the said rear wall and extending at an inclination at the back of the whole of the matter to be displayed, and triangular retaining plates detachably secured to the said side walls and inwardly bent as to their front and rear edges for maintaining the said front screen and plate and the said reflecting panel in their respective positions against the said front frame and rear wall.

45 2. An exteriorly illuminated sign comprising in combination, a V shaped casing open as to the upper portion thereof and consisting of a front frame and rear wall and of two side walls, a screen adapted to display the matter to be exhibited and located within

the said front frame, a plate of ground glass disposed immediately behind the said front displaying screen, a reflecting panel of ribbed mirrored glass supported by the said rear wall and extending at an inclination at the back of the whole of the matter to be displayed, and means for maintaining the said front screen and plate and the said rear reflecting panel in their respective positions within the sign, the side walls of the said casing being furnished with inwardly bent portions which are adapted to afford a means of suspension for the sign and which are cut-away at their front and rear extremities to enable the said front screen and plate and the said rear reflecting panel to be inserted in and removed from the said casing.

3. An exteriorly illuminated sign comprising in combination, a V shaped casing open as to the upper portion thereof and consisting of a front frame and rear wall and of two side walls, a screen adapted to display the matter to be exhibited and located within the said front frame, a plate of ground glass disposed immediately behind the said front displaying screen, a sheet of coloured transparent material interposed between the said front displaying screen and plate of ground glass for colouring the displayed matter, a reflecting panel of ribbed mirrored glass supported by the said rear wall and extending at an inclination at the back of the whole of the matter to be displayed, and triangular retaining plates detachably secured to the said side walls and inwardly bent as to their front and rear edges for maintaining the said front screen and plate and the said rear reflecting panel in their respective positions against the said front frame and rear wall, the side walls of the said casing being furnished with inwardly bent portions which are adapted to afford a means of suspension for the sign and which are cut-away at their front and rear extremities to enable the said front screen and plate and the said rear reflecting panel to be inserted in and removed from the said casing.

In testimony whereof I have signed my name to this specification.

ROY AUSTIN.
